(57) **CLAIM**

The ornamental design for a millstone as shown and described.

DESCRIPTION

FIG. 1 is a front, right, and bottom perspective view of a millstone, showing my new design;

FIG. 2 is a rear, left, and top perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom view thereof; and,

FIG. 9 is detailed view taken from encircled portion labeled "9" in FIG. 5.

The short-dash and long-dash broken lines in FIGS. 5 and 9 denote the boundaries of the detail areas and form no part of the claimed design. The even broken lines in the drawings are portions of the millstone and form no part of the claimed design.

1 Claim, 9 Drawing Sheets
